Primary Examiner — Ricky Pham(74) *Attorney, Agent, or Firm* — Stetina Brunda Garred & Bruker; Lowell Anderson(57) **CLAIM**

The ornamental design for a chafing pan, as shown and described.

DESCRIPTION

FIG. 1 is a top perspective view of the chafing pan of this invention;

FIG. 2 is a bottom perspective view of the chafing pan of FIG. 1;

FIG. 3 is a front view of the chafing pan of FIG. 1, with the back view being a mirror image thereof;

FIG. 4 is a right-side view of the chafing pan of FIG. 1, with the left-side view being a mirror image thereof;

FIG. 5 is a top view of the chafing pan of FIG. 1; and,

FIG. 6 is a bottom view of the chafing pan of FIG. 1.

1 Claim, 3 Drawing Sheets(56)
